PROCESS AND APPARATUS FOR SPINNING
ARTIFICIAL SILK ON BOBBINS

Hendrik Gerardus van der Waals, Arnhem, Netherlands, assignor to American Enka Corporation, Enka, N. C., a corporation of Delaware

Application January 22, 1934, Serial No. 707,791
In Germany March 16, 1933

5 Claims. (Cl. 18—8)

This invention relates to bobbin spinning wherein a novel method and apparatus is provided therefor. It is more particularly applicable to two of the general types of ordinary bobbin spinning machines which include what is known as the single spinning machine and the double spinning machine.

The single spinning machine consists of a series of spinning heads, each spinning head including one spinnerette and two bobbins. In operation the filaments are extruded from the spinnerettes and spun onto every other bobbin, the alternate bobbins in the series remaining stationary during the spinning period. Upon the completion of the spinning, the filaments from the spinnerettes are transferred to the alternate bobbins and a second spinning takes place while the full bobbins are being doffed.

In the double spinning machine a plurality of spinning heads is also employed, but in this case a spinnerette is provided for each bobbin in the series. When the spinning operation has been completed the filaments from a number of spinnerettes are transferred to one empty bobbin or waste roller and are spun in this manner during the doffing period of the full bobbins. The filaments being spun on the bobbin or waste roller during this stage cannot be utilized. Upon completion of the doffing, empty bobbins are placed on the spindles and the same operation again takes place.

Both of the above described processes present the disadvantage of spinning the filaments under tension and therefore a compact package results. This causes two very troublesome problems to arise. First, owing to the tightness of the wound mass it is very difficult to subject the package to after treating steps, which include washing, desulphurizing, bleaching, dying, etc.

Second, because of the rigidity of the bobbin the inner layers of filaments cannot shrink in the same manner as the outer layers thereby resulting in uneven shrinkage which finally results in an uneven dying throughout the package.

The present invention has for its object to provide a method of simultaneously rewinding one set of previously spun bobbins under substantially no tension while spinning an alternate set of bobbins.

A further object is the provision of an apparatus to successfully carry out the rewinding step in conjunction with the spinning step.

The invention can more clearly be described by referring to the drawing wherein similar reference characters represent like parts.

Fig. 1 is a diagrammatic front view of the apparatus, wherein the first stage of the spinning and rewinding operations is shown.

Fig. 2 is similar to Fig. 1 except that the spinning operation has been substantially completed, and the rewinding operation has been fully completed; and

Fig. 3 is also similar to Fig. 1 showing the new position of the filaments in the second spinning and rewinding operations.

Whereas any number of spinning heads may be employed, for the purpose of describing the invention only a part of a single spinning machine is shown in the figures including one complete spinning head and a portion of two spinning heads and may be placed close enough to the bobbin 3a so that a thread guide is unnecessary during the rewinding operation.

As shown in Fig. 1 the first spinning of the filaments 1 and 1a takes place on bobbins 2 and 2a respectively. As stated, the number of bobbins to be employed is optional and this much of the process is similar to that performed on the ordinary single spinning machine wherein the filaments from each spinnerette are wound on every other bobbin of a series.

In place of allowing the alternate bobbins 3 and 3a to remain idle, they are used to rewind previously spun bobbins. In order to effect this an additional loose running bobbin holder 4 is provided for each pair of bobbins. The bobbin holder 4 may be placed in any convenient position near the driven bobbin. One location, as shown in the drawing, is below and between each pair of driven bobbins designated at 4, 4a and 4b. While the filament 1 is being spun on bobbin 2, a rewinding is taking place from a previously spun bobbin 5 placed on the loose running bobbin holder 4, onto a bobbin 3a.

Fig. 2 shows that stage of the operation where the spinning of the filament 1 onto the bobbin 2 has been substantially completed and the rewinding from the bobbin 5 onto the bobbin 3a has been entirely completed.

Fig. 3 exemplifies the next step in the operation wherein the first set of bobbins 2 and 2a have been spun and transferred to the bobbin holders 4 and 4a and the alternate bobbins 3 and 3a have been rewound and removed for further treatment. The now empty bobbins 4 and 4a have been transferred to the bobbin holders from which the bobbins 3 and 3a have been removed, and the filaments 1 and 1a have been transferred to these bobbins 3 and 3a. The completed bobbins 2 and 2a have been transferred to the loose

running bobbin holders 4 and 4a. These bobbins are rewound on empty bobbins in positions 2 and 2a. Thus the simultaneous spinning and rewinding operations again take place as previously described.

Owing to the fact that the bobbins are rewound from loose running spindles, a loosely wound mass is formed which tends to make an excellent package for after treatment. Another 10 advantage is that the previously innermost layers of filaments which could not contract because of the rigidity of the bobbin holders are now the outermost layers and can shrink normally.

15 The bobbins which are being first spun from the spinnerettes are conidized, which decreases their speed of rotation towards the completion of the package, while the alternate bobbins are being rewound and driven at approximately the 20 initial speed of rotation of the first spun bobbins. Therefore the rewinding of the package is completed before the spinning operation is finished. In this manner the rewound bobbins may be doffed and empty bobbins replaced during the 25 completion of the spinning stage.

Whereas the invention has been described as applied to the single spinning machine it may, if desired, be employed with the double spinning machine in which case it will be necessary 30 to add a second positively driven bobbin and a loose running bobbin holder for every spinning head.

It is not meant that the invention be interpreted as applied to the drawing, as various 35 modifications may be made to fall within the scope of the invention.

Having thus described my invention, what I claim is:

40 1. In a process for the manufacture of artificial silk on spinning machines which contain two series of driven bobbins in alternate relationship, in which the bobbins of one series are normally idle during the spinning period, the step which comprises utilizing the series of nor-

45

mally idle bobbins by rewinding filaments thereon simultaneously with the spinning of freshly extruded filaments on the other series of bobbins.

2. A process according to claim 1 in which the rewinding operation is terminated prior to the completion of the spinning operation whereby the rewound bobbins may be replaced by empty bobbins before the doffing of the freshly spun bobbins. 80

3. In a process for the manufacture of artificial silk on spinning machines which contain a series of freely rotatable bobbins and two series of driven bobbins in alternate relationship, in which the bobbins of one series are normally idle during the spinning period, the steps which comprise, utilizing the series of normally idle bobbins by rewinding filaments thereon from the series of freely rotatable bobbins, simultaneously spinning freshly extruded filaments on the other series of bobbins, terminating the rewinding operation prior to the completion of the spinning 85 step, removing the rewound bobbins and replacing therefor empty bobbins, transferring the freshly spun bobbins to the freely rotatable bobbin holders and repeating the above cycle. 90

4. An apparatus for the manufacture of artificial silk comprising in combination two series of driven bobbins in alternate relationship in which the bobbins of one series are normally allowed to remain idle during the spinning period, a series of loose running bobbin holders, means 100 for spinning on one of the said series of bobbins and means for utilizing the other of the said series of bobbins which are normally allowed to remain idle, by simultaneously rewinding thereon filaments from previously spun bobbins located on the series of loose running bobbin 105 holders. 110

5. An apparatus as defined in claim 4 which includes means for terminating the said rewinding operation prior to the spinning step whereby the rewound bobbins may be replaced by empty bobbins before the doffing of the freshly spun bobbins. 115
